HECTOR VASSILIADI, OF LONDON, ENGLAND.

MECHANICAL UNDERFEED STOKER.

1,371,529.

Specification of Letters Patent. Patented Mar. 15, 1921.

Application filed September 18, 1918. Serial No. 254,551.

To all whom it may concern:

Be it known that I, HECTOR VASSILIADI, a subject of the King of Italy, residing at 64 Westbourne Terrace, Hyde Park, London, 5 W., England, have invented certain new and useful Improvements in Mechanical Underfeed Stokers; and I do hereby declare the following to be a full, clear, and exact description of the invention, such as will enable others skilled in the art to which it appertains to make and use the same.

This invention relates to mechanical underfeed stokers for providing a continuous feed of green fuel from a hopper into a furnace, and refers to stokers of this kind in which the fuel is introduced into the furnace under a bed of incandescent fuel.

In accordance with this invention I make the grate of a number of units which receive, by suitable mechanical means, a continuous motion after the manner of an endless belt; the space or cavity formed between two consecutive units is filled with fuel as the units pass a hopper, each unit after it enters the furnace being gradually tilted in such manner that the fuel resting thereon is raised, so that it ultimately penetrates, and mingles with, and forms part of, the overlying stratum of incandescent fuel. This underlying stratum is then pushed in the opposite direction to which it has hitherto been traveling in the furnace by means of a system of reciprocating rakes; and forms a continuous stratum of incandescent fuel which covers the stratum of green fuel.

The periodical strokes of the rakes are so regulated that the incandescent fuel will gradually advance from the fire bridge end toward the front of the furnace and be consumed as it reaches the front so that only the incombustible part of the fuel is left, and this is then ejected from the furnace, by the action of the rakes aforesaid, through openings or passages provided for the purpose, air under compression being blown into the apparatus in such a manner as to pass through the grate and the fuel carried by the grate, as well as being blown into the rakes which are made hollow and with 50 openings therein through which the air issues onto the fuel bed.

By these means the green fuel, as it is introduced into the furnace and travels under the incandescent fuel, is gradually heated and its volatile combustible constituents are distilled off which latter mingle

with the air coming through the grate and pass through the bed of incandescent fuel overhead—the combustion of these gases and the incandescent fuel being completed 60 by the admixture of the air issuing immediately over the fuel bed from the rakes.

The elements forming the traveling grate are linked together in such manner as to permit them to be displaced relatively to one 65 another, and also to permit them to receive, by the means hereinafter described, the common continuous motion required. Any two consecutive elements as they pass under a hopper at the front of the furnace, are in 70 such relative position as to form between them a cavity or space into which the fuel drops by gravity from the hopper. As they thereafter progress into the furnace their relative position is gradually modified by 75 the tilting action aforesaid, and the cavity between them is deformed and reduced in capacity, so that the fuel deposited therein is gradually raised and introduced into the bed of incandescent fuel above. 80

And in order that the details of construction and action of my invention may be clearly understood I will now proceed to describe same with reference to the accompanying drawings and figures of reference 85 marked thereon.

Figure 1 is a side elevational view of the stoker constructed in accordance with this invention and shown in position within the furnace, the latter being in section 90 and the rakes being represented in their vertical or operative position; Fig. 2 is a plan view of the stoker, partly in section, and Fig. 3 an end view, partly in section; Fig. 4, in sectional elevation, illustrates the 95 connection of one of the rakes with the air box supplying air to said rakes; Fig. 5 is a cross section of one of the rakes; Fig. 6 is a cross section of a rake trunnion showing it in toothed engagement with the rack upon 100 which it travels; Fig. 7 is a section of the front end of the air box, and Figs. 8, 9 and 10, are detail views of the mechanism for actuating the rakes.

In carrying my invention into practical 105 effect I make the fire grate of a number of separate elements 1, each formed essentially of two rectangular surfaces (hereafter called: the one a plane surface 2, and the other a curved surface 3), which are disposed at a fixed angle to each other, with the apex 4 of the angle turned upward, and 110

2

perpendicular to the longitudinal axis of the grate. In their rearward movement through the furnace the plane surfaces 2 of the grate elements pass beneath and parallel 5 with the under face or wall of the fire bridge 5, and the curved surfaces 3 on the side are disposed opposite the furnace front. Each element is supported from underneath by two parallel carrier bars extending from 10 side to side of the grate and hereafter called:—the forward one (in the direction of movement) the tractor carrier bar 6 and the rear one the trailer carrier bar 7. The tractor bars 6 are longer than the trailer 15 bars 7 and in their forward movement are parallel and describe an imaginary surface distinct from another imaginary surface described by the displacement of the trailer bars. Each tractor bar 6 is linked near its 20 ends to the following tractor bar, and these ends travel in guides 8, which as shown may be in the nature of strips or the like fixed to each of the two side frames or walls 9 of the casing 10 inclosing the grate. The 25 links 11 connecting the tractor bars form an endless chain on each side of the grate and pass over sprocket wheels 12, 13 at the front and rear ends of the grate, so that the revolution of these sprocket wheels forces the 30 two link-chains to travel continuously forward, carrying with them the grate elements from the front, under the hopper 14, to the rear, under the fire bridge 5 and thence over the rear sprocket wheels 13 and under 35 the grate proper toward the front sprocket wheels 12; and over these latter to their original position under the hopper; the operations being repeated indefinitely.

The trailer bars are not linked, and their 40 ends travel freely along in another pair of guides 15 with which the side walls are provided; the guides for the trailer carrier bars are fixed on vertical planes parallel to the vertical planes of the tractor bar guides, and 45 secured to these latter by brackets; or the trailer guides may be carried directly on brackets fixed to the side frames. When the trailer bars 7 slide forward in their guides 15 under the action of the grate elements 50 to which they are attached, they describe an imaginary plane surface; the tractor bars 6 are at all times parallel to this imaginary surface but they slide in their own guides, the distance between these tractor bars and the imaginary surface described by the movement of the trailer bars varying whenever the direction of the tractor bars' guides varies; and consequently the forward parts of the grate elements then tilt around 55 the trailer bars as pivots. When the distance between a tractor bar and this imaginary plane is a minimum, the corresponding grate element is tilted downward to a maximum extent; as this distance increases on 60 the contrary, the forward part of the grate

element is tilted upward around its trailer bar as a pivot.

As the grate elements constituting at any time the fire grate proper advance in the furnace under the tractive effort of the 70 sprocket wheels acting on the bar-links to which are fixed the tractor bars 6, the grate elements travel between two cheeks, or side plates 16 fixed to the coping 17 over the upper edge of the side walls 9, and these cheeks 75 limit the cavity 18 produced between two consecutive grate elements so that it has practically the shape of a triangular prism or trough in which the coal is deposited from the hopper as the grate elements pass 80 immediately underneath it. As the grate advances in the furnace the grate elements are gradually tilted upward and thereby the coal-laden trough is gradually deformed and its capacity decreases, the coal it contains being gradually heaved upward. By the time a grate element has reached the firebridge the tilting upward has proceeded to such an extent that its plane surface is flush with the plane surface of the grate-element 85 preceding it, and the cavity between them has completely disappeared, all the coal contained in it having been then heaved upward above the level of the flush plane surfaces passing under the firebridge. 90

The grate elements then continue their travel under the fire-bridge, which stops and sweeps off any fuel resting on their plane surfaces, and they move on over the rear sprocket wheels to the underpart of the 100 grate, thence over the front sprocket wheels to their original position under the hopper; the direction of the tractor guides being such that during the return part of the travel of the grate elements to the point under the hopper the downward tilting movement of the grate elements takes place and reaches its maximum as said elements pass under the hopper. The cavity or trough is reformed in this way between two consecutive 105 grate elements and has a maximum capacity under the hopper as a fresh charge of fuel drops therefrom into it. 110

The sprocket wheels on each side of the grate revolve in planes parallel to the planes 115 of the tractor and trailer guides, and between these two.

The two pairs of sprocket wheels are keyed to shafts 19 which extend beyond the side walls 9. Either or both of these shafts 120 drive the moving grate through the medium of a transmission shaft extending from the front to the rear of the boiler and engaging the sprocket wheel shaft through worm wheel gearing or similar arrangements suitably protected by an inclosed gear case, the whole transmission gear being located beyond the outer side of the side walls. 125

The power actuating the gear may be supplied either by belt from a line shaft, elec- 130

tric motor, or small steam engine, by suitable transmission.

The whole apparatus is inclosed in an air-tight casing, except that part covered by the 5 grate-elements constituting at the time the grate proper. Air is blown under pressure into the casing through the duct 22^a and issues therefrom through the spaces between adjacent grate elements forming at the time 10 the grate proper. An air tight trap door 20 immediately in front of the hopper serves to feed fuel upon the grate for starting purposes.

A number of horizontally arranged rakes 15 21 at a definite distance apart, have a periodical reciprocating action longitudinally of the furnace, whereby they spread and push the fuel over the grate toward the front of the furnace when they move from the 20 back of the grate toward the front; when on the point of starting on their return stroke they are made to rock around their longitudinal axes through about a right angle by means of mechanism hereinafter described. 25 These rakes in cross section are so formed that after this oscillation they clear the fuel bed on their return (or idle) stroke (the action being similar to feathering in rowing). When on the point of starting another forward (or active) stroke, the rakes are 30 righted to their original position by the action of the above mentioned mechanism and then again advance, pushing and spreading in front of them the fuel that has risen above 35 the level of the lowest edge of the rake by the action of the moving grate during the time of one complete reciprocating stroke of the rakes.

On each side of the top edge 17 of the 40 casing lies a long prismatic box 22 of rectangular section and having the length of the furnace. These boxes are hereinafter called the air boxes. The inner faces of these boxes are pierced with circular holes 45 forming bearings in which fit hollow trunnions 23 fixed to the ends of the rakes; so that when these air boxes are simultaneously made to advance or recede (over roller-bearings 24) on the edge of the air-box they 50 carry with them the rakes, giving them a reciprocating movement over the fuel bed which they span.

Through the front end of each air box passes a square bar 25 which passes under 55 the trunnions and reaches beyond the rear-most rake; this bar has a rack 26 on its upper face, which engages pinions 27 fixed to the trunnions, so that when the bar is pulled forward or pushed backward the rack 60 acts on the pinions forming part of the rake system.

This bar 25 extends beyond the front end 65 31 of the air box 22 and at the point where it passes through the front end of said air- 65 box it carries a sleeve 28 fixed to the bar,

which slides tightly in a hole in the front end of air-box. This sleeve 28 has a length determined by the amount of displacement of the bar necessary for the rack acting on the trunnions to make these latter and with 70 them the rakes oscillate through an angle of about 90°. On opposite ends of the sleeve 28 are two collars 29 and 30 which butt against each side of the front end 31 of the air box and limit the length of forward and 75 backward movement of the bar in the air-box.

When the bar is pulled outward the rack thereon forces the trunnions to revolve, and just as the inner collar 30 abuts against the 80 end of the air-box the rakes attain the upright position represented in Fig. 1, it being assumed that in that figure the bar is indicated in its extended position. Thereafter if the bar is still pulled forward it drags 85 with it the air-box, with the rakes locked in an upright position by the rack. Should the bar now be pushed backward at the end of this stroke the rakes rotate the trunnions in the opposite direction and the rakes, revolving, return to their original horizontal position which enables them to clear the surface of the fuel bed, the outer collar 29 butts against the end of air-box, and if the bar is still pushed backward it pushes the 95 air-box back, with the rakes locked in horizontal position by the rack. At the end of this rack stroke, the operation described is repeated whereby the rakes are righted and moved forward by the air-boxes which 100 are pulled out of the furnace by the two bars, thus constituting the forward or active stroke.

The air boxes are pulled outward and pushed backward by the following means; 105 the bar 25 extends beyond the end of air-box and carries a rack 32 on two opposite faces. Each rack engages a pinion 33 keyed to axles 34, 35 in line with two axles 36, 37 with which they can be connected alternately 110 by means of clutches 38, 39 sliding on these latter axles but revolving with them at all times. One of these axles carries a driving gear or pulley 40 and the two axles revolve at all times simultaneously in the same direction through the medium of chain gearing or of toothed wheels 41, 42 keyed to their respective shafts, and an idle wheel 115 in gear with both wheels. When one of the clutches is engaged, the other being free, 120 the pinion carried by the axle which prolongs the axle carrying the engaged clutch has to revolve with this axle, and the rack of the air-box bar is moved in one direction.

The driving axle carries a keyed spur-wheel 43 engaging a toothed wheel 44 which revolves loosely on the counter axle 37; this toothed wheel carries two cams 45, 46 which act on the lever 47 carrying the clutches so that during one half revolution of this 130

toothed wheel one of the clutches is engaged and the other clutch is free, while during the other one-half revolution the action of the clutches is reversed. The 5 length of stroke of the air-boxes is determined by the ratio between the diameters of the keyed spur-wheel 43 and the loose toothed wheel 44 revolving on the other shaft.

10 As soon as the first clutch is freed and the second clutch is engaged the axle of the latter is connected with the axle in its prolongation carrying the second pinion which acts in an opposite direction to the first pinion on the rack of the air-box bar, and consequently this latter is now pushed in an opposite direction to what it was proceeding previously under the action of the first pinion. When the other cam of the toothed 15 wheel again reverses the action of the clutches after one-half revolution of the toothed wheel the counter-shaft 37 again becomes idle and the driving shaft 36 acts directly on the rack of the air-box bar; the 20 operation being repeated indefinitely.

The rakes 21 whose length equals the breadth of the grate, are hollow castings (see particularly Fig. 5) the cross section 48 being roughly triangular. A cylinder or 25 tube 49 is cast in the center of the rake shell, with a longitudinal slot 50 in the tube connected by two parallel walls 51, 52 with a corresponding longitudinal slot 53 in one of the faces of the rake shell.

30 Special lids 54 form the ends of the rakes, capping simultaneously the rake shell and the rim of the central tube. Each lid comprises a hollow cylinder 55 of short length, one end of which presses against the rim 35 of the central tube forming a water-tight and air-tight joint, the other end entering the air-box and forming the trunnion carrying the rake. A collar 56 is cast around this 40 hollow cylinder and has a contour corresponding to the section of the rake shell, so that when the one end of the hollow cylinder 45 presses against the inner tube the collar presses against a ledge on the inner end of the rake shell forming a water-tight joint.

50 The two lids on each side of every rake are held in position by stays 57 running through the rake.

When air is blown into the air-boxes 22 by means of a flexible tube 58 it can only 55 escape through the hollow trunnions formed by the cylindrical part of these lids or caps, and passes on by the inner tube through the slots on the inner rake-tube and the face of the rake-shell into the furnace, where it 60 completes the combustion of the fuel.

The rakes are water cooled. A pipe 59 is arranged longitudinally inside the air-box and water is supplied to it by means of a flexible tube 60; and opposite each trunnion a small tube 61 branches off from the

main tube exactly in the position of the axis of rotation of the rakes. This branch tube penetrates by a cross tube 62 through the collar into the inclosed space formed by the rake-shell, the inner tube and the two end 70 lids, so that the cooling-water enters at one end of the rake, circulates therethrough and issues at the other end by an identical arrangement, one air-box serving for the cooling water inlet and the other air-box for its 75 outlet.

As the branch pipe 61 rotates with the rake it is connected to the T-piece 63 on the main pipe 59 by a water tight gland 64 allowing it to rotate freely around its axis. 80

In their reciprocating action the rakes push the fuel on the surface of the bed toward the front of the furnace, and by the time this fuel reaches the vicinity of the hopper the combustible part of it has been 85 consumed, leaving behind only the ashes and clinker to be disposed of. The rake nearest the furnace front, during its forward or active stroke advances quite close to the hopper, as shown by the broken line 65, and any 90 clinker and ashes caught between the two air-boxes and this rake are pushed and pressed by the flat side of the rake against the hopper. At this same level one or more openings 66 in the hopper are provided for 95 the passage there-through of the ashes and clinker which are thereby ejected from the furnace at each stroke of the rake.

The advantages to be derived from the use 100 of an underfeed stoker as above described are that during the time the green fuel lies under the incandescent fuel it distils, and the volatile hydrocarbons pass through the bed of incandescent fuel above, where they 105 are burnt with the air passing through the grate units and that issuing through the rakes. As the green fuel gradually advances in the furnace it undergoes a coking process from the heat radiating on it and by the time the green fuel has reached the fire-bridge 110 end it has given up its volatile constituents and, thereafter, as it is pushed by the rakes toward the furnace front over the oncoming green fuel it forms a layer of incandescent 115 solid fuel burning through the medium of the air issuing through the grate and from the rakes. The fuel is thus gradually consumed with the necessary amount of air and by the time it reaches the furnace front only ashes and clinker remain to be disposed of, 120 and these are expelled automatically through the openings 66 in the hopper by the front rake 65 in the manner above described.

What I claim is:

1. A mechanical stoker comprising the 125 combination of an endless traveling conveyer consisting of a plurality of connected elements, means for driving the conveyer, a bridge wall adjacent to the conveyer, means for tilting the individual elements of the 130

conveyer in one direction with relation to each other at one end of the furnace so as to form pockets for the reception of fuel between adjacent elements at said end, and in the opposite direction with relation to each other as said elements approach the bridge wall, so as to cause the pockets to disappear by bringing the fuel-carrying surface of each element into a position wherein it is parallel to the direction of movement of the element and close to the bridge wall, a plurality of rakes above the conveyer, and means for operating the rakes to move the fuel in a direction opposite to the direction of movement of the fuel carried by the conveyer.

2. A mechanical stoker comprising the combination of an endless traveling conveyer consisting of a plurality of connected elements each of which has a fuel-carrying surface and a second surface extending downwardly from one edge of the fuel-carrying surface, means for driving the conveyer, fuel-supplying means, and means for regulating the angular disposition of the elements of the conveyer with relation to one another so as to provide pockets for the reception of fuel between the fuel-carrying surface of one element and the downwardly extending surface of an adjacent element when those elements are in proximity to the fuel-supplying means and to turn each element with relation to the adjacent element as it moves away from the fuel-supplying means to raise the fuel upon its fuel-carrying surface.

3. A mechanical stoker comprising the combination of an endless traveling conveyer, consisting of a plurality of connected elements each having a fuel-carrying surface and a second surface extending downwardly from one edge thereof, fuel-supplying means and a bridge wall adjacent to which the conveyer elements pass and means for regulating the angular disposition of the successive elements with relation to one another as they move from the fuel-supplying means to the bridge wall so as to form pockets for fuel between the fuel-carrying surface of one element and the downwardly extending surface of the adjacent element when those elements are in proximity to the fuel-supplying means and to turn the elements independently of and relatively to each other to positions in which their fuel-carrying surfaces are parallel to the direction of travel when they pass in proximity to the bridge wall.

4. A mechanical stoker comprising the combination of an endless traveling conveyer consisting of a plurality of connected elements each of which has a fuel-carrying surface and a second surface extending downwardly from one edge of the fuel-carrying surface, means for driving the con-

veyer, fuel supplying means, means for regulating the angular disposition of the successive elements of the conveyer with relation to one another so as to provide pockets for the reception of fuel between the fuel-carrying surface of one element and the downwardly extending surface of an adjacent element when those elements are in proximity to the fuel-supplying means and to turn each element relatively to the adjacent element as it moves away from the fuel-supplying means to raise the fuel upon its fuel-carrying surface, a plurality of rakes above the conveyer, and means for operating the rakes to move the fuel in a direction opposite to the direction of movement of the fuel carried by the conveyer.

5. A mechanical stoker comprising the combination of an endless traveling conveyer consisting of a plurality of connected elements, a fuel-supplying means and a bridge wall adjacent to which the conveyer moves, means for varying the positions of the successive elements of the conveyer with relation to one another as they move adjacent to the fuel-supplying means so as to form pockets for the reception of fuel from the fuel-supplying means and thereafter to force the fuel received into the pockets upwardly into an overlying bed of fuel as the elements move away from the fuel-supplying means, a plurality of rakes above the conveyer, and means for operating the rakes to move the fuel in a direction opposite to the direction of movement of the fuel carried by the conveyer.

6. A mechanical stoker comprising the combination of an endless traveling conveyer consisting of a plurality of connected elements, a fuel-supplying means and a bridge wall adjacent to which the conveyer moves, means for varying the positions of the successive elements of the conveyer with relation to one another as they move adjacent to the fuel-supplying means so as to form pockets for the reception of fuel from the fuel-supplying means and thereafter to force the fuel received into the pockets upwardly into an overlying bed of fuel as the elements move away from the fuel-supplying means, a plurality of rakes above the conveyer, means for operating the rakes to move the fuel adjacent thereto, and means for admitting air to the bed of fuel through the rakes.

7. A mechanical stoker comprising the combination of an endless traveling conveyer consisting of a plurality of connected elements, a fuel-supplying means, means for varying the positions of the successive elements of the conveyer with relation to one another as they are moved toward the fuel-supplying means so as to form pockets between successive elements for the reception of fuel from the fuel-supplying means

and thereafter to force the fuel received into the pockets upwardly into the overlying body of fuel as the elements move away from the fuel-supplying means, rakes located above the conveyer for moving the fuel adjacent thereto in a direction opposite to the direction of movement of the fuel

carried by the conveyer, and means for supplying air to the fuel adjacent the conveyer and also to the fuel adjacent to the rakes, ¹⁰ both of the air-supplying means being under the control of the operator.

In testimony whereof I affix my signature.
HECTOR VASSILIADI.
